UNITED STATES PATENT OFFICE

159,001

CHAIN FOR A BRACELET OR SIMILAR ARTICLE

Alfred Pinson, Stamford, Conn., assignor to Apex
Accessories Co., Inc., Greenwich, Conn.

Application August 11, 1949, Serial No. 4,419

Term of patent 7 years

(Cl. D45—16)

To all whom it may concern:

Be it known that I, Alfred Pinson, a citizen of the United States, residing at Stamford, in Fairfield County, State of Connecticut, have invented a new, original, and ornamental Design for a Chain for a Bracelet or Similar Article, of which the following is a specification, reference being had to the accompanying drawing, forming part thereof.

Figure 1 is a perspective view of a fragment of a chain for a bracelet or similar article, showing my new design;

I claim:

The ornamental design for a chain for a bracelet or similar article, as shown.

ALFRED PINSON.
